UNITED STATES PATENT OFFICE.

LEWIS ANDREW STINSON, OF OAK PARK, ILLINOIS.

METHOD OF PREVENTION OF DUST EXPLOSIONS AND FIRES IN MILLS AND ELEVATORS.

Application filed December 31, 1924. Serial No. 759,194.

My invention relates to a method of dusting and sweeping mills and elevators and similar buildings and at the same time rendering the dust and sweepings noncombustible so that regardless of how much dust there may be produced in the atmosphere by reason of the dusting and sweeping the very act of dislodging this dust renders it in explosive and noncombustible.

10 It is well known that dust explosions are frequent and that dreadful explosions and fires have resulted from the dust igniting in mills and elevators.

These explosions frequently take place 15 while there is dusting and sweeping going on, so that the very act of cleaning up the dust is a hazardous matter, because the dust which is swept and brushed down floats in the atmosphere to the point of saturation 20 where a spark from any source ignites it in the well known manner that causes explosions.

At other times a sudden shock or jar dislodges dust that becomes ignited from 25 various causes. In the normal service of the machinery in such a mill dust accumulates in the air to the point where it becomes explosive and gets ignited by various accidental means.

30 It is substantially impossible to always keep all the dust sufficiently cleaned up in the flour mills and elevators to insure complete safety against dust explosions, and the best method that is known to me is to provide a means of cleaning up or removing the dust in a manner that will make the dust in explosive and noncombustible really before it is dislodged from any place of rest.

I accomplish this result by my method 40 herein set forth.

Reference will be had to the accompanying drawing which is diagrammatical only and involves a nozzle adapted to spray a liquid and as occasion requires a blast of 45 air along therewith, that will dislodge and blow down the dust from walls, machinery and other places of lodgment by the force of a spray. The liquid spray itself being composed of a solution which renders the 50 dust substantially fire proof and noncombustible. The spraying feature may be applied to the floor as well as to the other places as occasion requires.

55 Fig. 1 of the drawing indicates an operator using a nozzle in spraying the side of a wall which nozzle is connected to a pipe

and the pipe to a source of supply of compressed air and a source of supply under pressure of the liquid to be sprayed.

2 indicates the nozzle, and 3 the supply pipe connected therewith which receives its supply of compressed air by a hose connection 4, connected to any suitable supply of compressed air.

5 indicates the hose connected to any suitable supply of fire proofing solution under pressure. 6 indicates the wall which is being sprayed or dusted by the spray and air nozzle as described.

In localities or places wherein the dust 70 accumulates rapidly and particularly in dangerous places such as around drying machines or in heads, boots and spouts that require cleaning frequently and in places not convenient for an operator to reach with a 75 hand-controlled nozzle, I will provide fixed piping and fixed spray nozzles under the control of suitable valves to be dusted out and protected by an operator as often as occasion may require.

A relatively small percentage of a fire 80 proofing solution when applied directly as a means of dislodging the dust renders the dust in explosive and at the same time fire proof when this dust becomes accumulated 85 in any sort of a mass on the floor or other spaces.

The solution that I prefer to use for this 90 purpose measured in units of about 35 gallons is substantially, sulphuric acid chemically pure, 1 quart, 6 pounds of bicarbonate of soda, mixed and dissolved in 35 gallons of water.

The method of mixing is to put the acid 95 and water together first and stir the soda in at the last.

Other solutions besides this may be used but this solution is found satisfactory. The 100 solution spray alone or volume of air which is sprayed along with this solution is sufficient, together with the force of the spray, to dislodge and blow the dust away from crevices in the walls and machinery and other places, and thus saturated with the watery solution the material falls to the floor 105 and is swept up and removed as a harmless inert material from the standpoint of explosions and fires.

The amount of solution that is mixed in 110 this dust is not sufficient to diminish the value of the product from the standpoint of its being used for feed where the dust in-

volved is desirable for that purpose, nor is the quantity of the solution sufficient to damage the dust thus treated to the point of injuring its storage or keeping qualities.

5 More dust explosions are caused in the very act of dusting and brushing down and cleaning up the premises than are caused by all other agencies, and by my method of doing the dusting work the possibility of 10 explosion is entirely eliminated.

What I claim is:

1. A method of preventing dust explosions, which involves the dislodging of the dust with the assistance of a spray containing a chemical which renders the dust inex- 15 plosive.

2. A method of dislodging dust which consists in spraying the same by means of an air blast in conjunction with a spray having

incorporated therewith a fireproofing in- 20 gredient adapted to render the dust inex- plosive.

3. A method of preventing fires and dust 25 explosions which consists in spraying the dust areas with a solution of a fire prevention material during the act of dislodging the dust.

4. A method of preventing fires and explosions in mills and elevators which consists 30 in spraying into the field of the dust a solution of a fire prevention material combined with an air blast adapted to dislodge the dust.

Signed at Chicago, in the county of Cook, and State of Illinois, this 26th day of De- 35 cember, 1924.

LEWIS ANDREW STINSON.
